UNITED STATES PATENT OFFICE.

TREAT T. PROSSER AND JAMES P. FREEMAN, OF CHICAGO, ILLINOIS; SAID FREEMAN ASSIGNOR TO THE HOME TELEPHONE COMPANY, OF ILLINOIS.

ELECTRIC TELEPHONE.

SPECIFICATION forming part of Letters Patent No. 257,610, dated May 9, 1882.

Application filed July 21, 1881. (No model.)

To all whom it may concern:

Be it known that we, TREAT T. PROSSER and JAMES P. FREEMAN, citizens of the United States, residing at Chicago, in the county of Cook and State of Illinois, have invented certain new and useful Improvements in Electric Telephones; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 This invention relates to electric telephones adapted to the transmission and reproduction of articulate speech by means of electrical impulses or waves traversing a circuit.

Our improvement (shown in connection with 20 an instrument more particularly intended for use as a receiver) consists in constructing the vibrating diaphragm with a central hemispherical depression, the convex side of which faces the permanent bar-magnet, and is arranged to be in close proximity to the end thereof. The effect of this construction is that the articulation of the instrument closely resembles natural speech, which it reproduces in a full tone of considerable volume.

30 In order that our invention may be clearly understood, we have illustrated in the annexed drawings and will proceed to describe the best form thereof at present known to us.

Figure 1 is a side elevation of a telephonic instrument embodying our improvement. Fig. 35 2 is an axial section of the same. Fig. 3 is an edge view of our improved vibrating diaphragm.

The same letters of reference indicate like 40 parts in all the figures.

The different parts of the instrument are mounted on a tubular body, A, of wood, vulcanized rubber, or other suitable material. The head a of this tube is covered by the 45 vibrating diaphragm B, the flat annulus b of which is confined around its periphery between a shoulder, a', on the head a, and a similar shoulder, c', on the cap C, which is screwed upon the head and covers the diaphragm, being provided with the usual central orifice, c, and the outwardly-flaring mouth. The central portion of the diaphragm is depressed, so as to form a hollow hemisphere,

b', under the orifice c of the cap C. The diaphragm may be struck up into form; but we 55 find it to be very perfect in action when it is made of a flat annulus, to the inner edge of which the base of the hollow hemisphere is soldered or brazed. We have constructed some 60 of these diaphragms in which the area of the base plane of the hemisphere is about one-third of the area of the flat annulus, and have found them to act admirably; but this proportion may be considerably varied. The hemispherical portion b' of the diaphragm extends 65 into a chamber formed in the head a, and is in close proximity to one end of the permanent bar-magnet D, the other end of which is supported by a screw, d, swiveled in the cover A' on the other end of the body of the 70 instrument. Thus by turning the screw d the permanent magnet D may be adjusted to the proper point with reference to the diaphragm. The upper end of the permanent magnet is 75 surrounded by a helix, E, the ends of which are in electrical connection with the respective binding-screws F and G, to which the conducting line-wires are to be attached.

The depression b' of the diaphragm need not be exactly hemispherical, although we have 80 obtained excellent results with that form.

We do not claim a diaphragm the entire 85 vibratory surface of which is concavo-convex. The experimental use of such a diaphragm led to the invention of the hereinbefore-described diaphragm, which, for receiving purposes at least, yielded far superior results.

Having thus described our invention, what 90 we claim is—

1. A telephonic instrument constructed with 90 a diaphragm the unsupported vibratory area of which is composed of a flat annulus and a central hemispherical depression, substantially as before set forth.

2. The combination, substantially as before 95 set forth, of the helix, the permanent magnet, and the diaphragm whose unsupported vibratory area is composed of a flat annulus and a hemispherical depression.

In testimony whereof we affix our signatures 100 in presence of two witnesses.

TREAT T. PROSSER.
JAMES P. FREEMAN.
